E. L. CANNON

PAINT MIXER

Filed Jan. 6, 1921

UNITED STATES PATENT OFFICE.

EDSEN L. CANNON, OF CLEVELAND HEIGHTS, OHIO, ASSIGNOR TO THE ERIE MANUFACTURING COMPANY, OF CLEVELAND, OHIO, A CORPORATION OF OHIO.

PAINT MIXER.

Application filed January 6, 1921. Serial No. 435,423.

To all whom it may concern:

Be it known that I, EDSEN L. CANNON, a citizen of the United States, residing at Cleveland Heights village, in the county of 5 Cuyahoga and State of Ohio, have invented certain new and useful Improvements in Paint Mixtures, of which the following is a specification.

This invention relates to improvements in 10 paint mixers.

It is the object of this invention to provide a paint mixer which can be easily and quickly assembled within a paint barrel or the like without the removal of the head of 15 the barrel; also to so construct the mixing apparatus that it can be inserted through a comparatively small hole in one head of the barrel and receive an agitating member which can be inserted through the bung 20 hole; furthermore to so construct the mixing attachment that the shaft which carries the agitating element can be inserted at the same time as the fixedly mounted support in the bottom of the barrel; and finally to 25 produce a mixing attachment which can be readily assembled and disassembled, which is simple in structure and hence not costly to manufacture, and one which can be removed from one barrel and applied to another, as may be desired.

Other objects of this invention will appear from the following description and claims when considered in connection with the accompanying drawings.

This invention is an improvement upon 35 the type of device disclosed in the patent to Riley 1,335,258, March 30, 1920, to which reference is here had for a fuller understanding of this invention.

Fig. 1 is a vertical transverse section through the barrel showing the mixing attachment in elevation and the manner of applying the same to the barrel; Fig. 2 is a vertical transverse section through the barrel 40 showing the mixing attachment fully assembled; Fig. 3 is a detail view of the ball and socket connection between the plug in the lower head of the barrel and the rotatable shaft which carries the agitating element; and Fig. 4 is a plan view of the socket forming member which is mounted upon the 45 inner end of the plug.

The barrel or container to which my attachment is to be applied is provided with 50 a comparatively small centrally disposed

opening in each of the heads and also the usual bung hole in the side wall. These openings are indicated in the drawings as 1, 2 and 3, respectively. The opening in the bottom head 4 of the barrel 60 is adapted to receive by screw thread engagement the plug 5 through which extends the rivet or bolt 6, the head of the plug being countersunk as indicated at 7 to house the head of the rivet. The 65 head 8 of the plug 5 is sufficiently shallow so as not to extend beyond the chime of the barrel. The inner end of the rivet 6 extends through the opening 9 in the socket forming member 10 and has formed thereon 70 a head 10' as a means of securing said socket forming member in fixed position upon the inner end of the plug 5. The socket forming member 10 is formed of suitable metal so as to enable the arms 11 75 thereof to be bent up about the ball member 12 which is connected by means of the neck portion 13 to the lower end of the shaft 14, and the arms 11 are given substantially the same shape as here illustrated so as to properly surround the ball 12. The ball 12 is adapted for rotatable engagement within the socket forming member so as to allow rotation of the shaft 14 which extends through the opening in the other head 2' for 80 operative engagement by a suitable crank 15. A cap 16 is provided with screw thread engagement with the head 2' as a means of closing the opening 2 and covering the exposed end of shaft 14 during the time when 85 the crank 15 is not applied for operation of the agitating device. The agitating element 17 may be of any suitable form, as for instance as shown in the patent above referred to. In this case the agitating element is 90 provided at its middle portion with a square opening for engagement with the shaft 14 which is also of square cross section and which extends through the opening in said agitating element. This element 17 is secured in position upon said shaft by means 95 of the collar 18 and its set screw 19.

The manner of applying my agitator to a barrel will now be briefly described. First of all the socket forming member 10 is 100 placed over the plain end of the rivet 6 as it extends through the plug 5 and the rivet is headed so as to secure these parts together. The arms 11 are then bent around the ball 12 so as to form a socket therefor. 110

The collar 18 is also positioned upon shaft 14. Then with the opening 2 closed by the screw threaded plug 16 the barrel is set in inverted position as indicated in Fig. 1, whereupon the shaft 14 carrying the collar 18 and connected by the ball and socket joint with the plug 5, is lowered through opening 1 and the agitating element 17 is inserted through bung hole 3 to the position indicated in Fig. 1 so as to bring the square opening of the agitating element directly beneath the lower end of the shaft 14. The same means may be employed for the insertion of the agitating element as disclosed in the patent above referred to. The shaft 14 is then fully lowered so as to bring the inner end thereof within the cap 16 and the plug 5 is firmly screwed into the opening 1. The barrel can then be turned to upright position and the crank applied to the free end of the shaft 14 upon removal of the cap 16. The agitating element can be placed at any height desired upon the shaft by properly positioning the collar 18 before insertion of the shaft into the barrel. The cross section of the ball and socket joint is of less width than the diameter of the opening 1 so as to permit insertion of the same therethrough in the manner above described.

30 Among the advantages resulting from this invention is that which resides in the fact that the shaft 14 and the plug 5 can be inserted in the barrel by a single operation. Thus I have provided a structure which is simple in its structure and operation and yet one which is highly efficient and not apt to get out of order in the use for which intended.

40 Other advantages flowing from this invention will be apparent to those who are familiar with the art to which it relates.

What I claim is:

1. An agitator comprising a plug adapted to be secured in the wall of a container, a 45 socket member carried upon the inner end of said plug, a shaft having a ball on one end thereof for rotatable engagement in said socket member and adapted to be inserted through the same opening as the plug, agitating means adapted to be secured upon said shaft, and means for rotating said shaft.

50 2. An agitator comprising a plug adapted to be secured in an opening in a wall of a container, a shaft having rotative connection with said plug, said plug and shaft when so connected being adapted to be inserted

through said opening, agitating means adapted to be secured upon said shaft, and means for rotating said shaft. 60

3. An agitator comprising a plug adapted to be secured in an opening in a wall of a container, a shaft having rotative connection with said plug, said plug and shaft when so connected being adapted to be inserted through said opening, agitating means adapted to be inserted through another opening in the container and to be secured upon said shaft, and means for rotating said shaft. 65

4. An agitator comprising a plug adapted to be secured in an opening in a wall of a container, a plurality of fingers secured to said plug and forming a socket within said container, a shaft having a ball on one 70 end thereof for rotatable engagement in said socket, and agitating means adapted to be secured upon said shaft. 75

5. An agitator comprising a plug adapted to be secured in an opening in a wall of a 80 container, a socket member secured to said plug and having a plurality of fingers forming a socket, a shaft having a ball on one end for rotative engagement with said socket, agitating means adapted to be secured upon said shaft, and means for rotating said shaft. 85

6. The combination with an assembled container comprising side, top and bottom walls and having spaced and relatively 90 small openings therein, a shaft, bearing means for rotatably receiving said shaft and mounting the same within said container, said shaft and bearing means being insertible as a unit through an opening in 95 one of said walls and said bearing means being adapted for connection to the said wall, agitating means adapted for securing upon said shaft and insertible through another of said openings, and means for rotating said shaft. 100

7. An agitator, comprising a plug adapted to be secured in an opening in a wall of a container, a headed pin extending through said plug, a socket member secured upon the inner end of said plug by the inner headed end of said pin, a shaft having a ball on one end thereof for rotatable engagement in said socket, and agitating means adapted to be secured upon said shaft. 105

110 In testimony whereof I hereby affix my signature.

EDSEN L. CANNON.
